Arthur B. Jenkins,
ATTORNEY.

UNITED STATES PATENT OFFICE.

WALTER MERRILLE GILBERT, OF EAST HARTFORD, CONNECTICUT.

ELECTRICAL RECEPTACLE.

1,404,953.

Specification of Letters Patent. Patented Jan. 31, 1922.

Application filed October 11, 1917. Serial No. 195,925.

To all whom it may concern:

Be it known that I, WALTER MERRILLE GILBERT, a citizen of the United States, residing at East Hartford, in the county of Hartford 5 and State of Connecticut, have invented a new and Improved Electrical Receptacle, of which the following is a specification.

My invention relates to the class of electrical boxes or receptacles that are more especially designed for temporary connection of electrical devices, as motors, employed for running machinery of various sorts, and an object of my invention, among others, is to provide a receptacle that will enable persons 10 having little knowledge of electricity, and especially unskilled help, to make the necessary connections without danger of personal injury or injury to the mechanism.

One form of device embodying my invention and in the construction and use of which the objects herein set out, as well as others, may be attained, is illustrated in the accompanying drawings, in which—

Figure 1 is a face view of a receptacle embodying my invention shown with the cover raised.

Figure 2 is a view in section through the same on plane denoted by dotted line 2—2 of Figure 1.

Figure 3 is a detail view of the plug block.

It is now customary to place machinery of certain kinds upon trucks, together with the motors for driving such machines, in order to readily locate such machines in different 35 places where they may be needed. Incidents of such uses occur in coal-yards, lumber-yards, concrete mixing plants, &c. Means for connection of the electrical cable to drive such motors are provided at the different 40 places where the machinery is required for use. Such machinery is often operated by unskilled labor, or employees unacquainted with the character of electricity and it is essential, therefore, that safe-guards shall be 45 provided to prevent accident from electrical sources in the operation of such machines.

My invention herein illustrated and described provides means whereby the connections for driving the portable machinery 50 may be readily made with little danger of injury to the persons making such connections irrespective of the conditions that may otherwise exist for the transmission of electrical currents through the body of such person and that might otherwise result in in-

jury owing to lack of knowledge as to the danger from such conditions.

In the accompanying drawings the numeral 5 indicates a receptacle or box that may be composed of any desired material 60 and that may have any desired form, and that may be provided with a cover 6 preferably hinged to one edge thereof. Plates 7 and 8 of any suitable insulating material are secured to the bottom of the box in any desired manner, and switch blades 9 of any usual construction are pivotally attached to posts 10, said blades being adapted to electrically engage contacts 11 in a manner common to devices of this kind.

The contacts 11 have the usual conducting wires 12—13 attached to them in any suitable manner and the posts 10 are electrically connected with terminals 14, such connection including fuses 15.

Contacts 16 are secured to the plate 7 and they are connected by wires 17 with the terminals 14. A socket 18 is formed in the plate 7 to receive a positioning pin 19 projecting from the bottom of a plug 20. 80 Blades 21 project from opposite sides of the plug and a cable 22 containing the usual conducting wires is secured to the plug in any suitable manner, said wires being connected through the plug with the blades 21 in a manner that will be readily understood by those having electrical knowledge, and for which reason specific description and illustration are omitted herein. Handles 23 project from the plug as a means for manipulating it. The contacts 16, positioning pin 19 and blades 21 are so positioned with respect each to the others that the two blades 21 can engage the contacts 16 only when the pin 19 is in the socket 18, and when the blades thus engage the contacts each blade must engage that contact that is especially designed for it to engage. That is, the plug is so constructed that when the pin is in its socket the blades will so engage the contacts 100 as not to "cross" the electrical current.

It will be understood that the wires in the cable 22 are, when the plug is in use, attached to the proper terminals of a motor used for driving machinery, my invention 105 being especially applicable in cases where portable machinery, as a concrete mixer mounted upon a truck, is transported from place to place about a yard or building, receptacles 5 being permanently located at such 110

points as it may be desired to use the machinery at.

A switch actuating shaft 24 is rotatably mounted upon the receptacle, as herein shown in the sides of the box, and an actuating finger 25 projects from the shaft through a loop 26 on a cross bar 27 of insulating material secured to the switch blades 9. This finger is of a length to project beyond the loop and overlie the plug 20 when the switch is closed, and, therefore, in such position with respect to the location of the plug that the latter cannot be inserted or removed without the finger being raised sufficiently 15 to cause the switch to be open. It will thus be apparent that the plug 20, when in place, cannot be removed until the finger 25 is raised from it sufficiently to disengage the blades 9 from the contacts 11 and thus "kill" 20 the box and also that the plug cannot be inserted without the actuating finger being raised sufficiently to disengage said blades and contacts and thus "kill" the box. This arrangement of the parts ensures the placing 25 of the plug before the switch blades 9 can be closed and also the opening of the switch before the plug can be removed and, therefore, removes all liability of danger especially to inexperienced help that is usually 30 employed in the operation of portable machinery of different kinds driven by electric motors and that is moved about from place to place where the operation of a machine may be required. It also removes all liability 35 to injury of the electrical and other machinery such as might be caused by im-

proper placing of the plug by such inexperienced help. A handle 28, located outside of the box, is connected with the shaft 24 as a means for operating it.

The cable is so attached to the plug and the single positioning pin is so arranged with respect thereto that any excess pull upon the cable will cause the pin to be pulled from its socket and that in such operation the 45 switch to be automatically opened thereby. It, therefore, follows that carelessness or oversight in moving the machinery to which the cable is attached will be counteracted as the detachment of the plug above described 50 will occur before force enough has been applied to break the wires.

In accordance with the provisions of the patent statutes, I have described the principles of operation of my invention, together with the apparatus which I now consider to represent the best embodiment thereof; but I desire to have it understood that the apparatus shown is only illustrative, and that the invention may be carried out by 60 other means.

I claim—

A receptacle including terminals for the inlet and outlet wires of an electric circuit, a removable plug, blades projecting from 65 opposite sides of the plug, and adapted to enter the open upper ends of terminals, and a pin projecting from the bottom of the plug in position to control insertion of each of the blades within the terminal intended 70 for it.

WALTER MERRILLE GILBERT
